GEORGE I. ROCKWOOD, OF WORCESTER, MASSACHUSETTS.

CONTROLLING APPARATUS FOR ALARMS.

1,185,545.

Specification of Letters Patent.

Patented May 30, 1916.

Application filed December 31, 1913. Serial No. 809,744.

To all whom it may concern:

Be it known that I, GEORGE I. ROCKWOOD, a citizen of the United States, residing at Worcester, in the county of Worcester 5 and State of Massachusetts, have invented a new and useful Controlling Apparatus for Alarms of which the following is a specification.

This invention relates to means for controlling the operation of alarms, particularly those used in connection with automatic fire sprinkler systems. Ordinarily, the main riser pipe supplying such a system is provided with a channel seated check valve which is caused to lift and uncover the channel seat whenever water flows past it, whether to supply an open sprinkler or as the result of a water hammer delivered by the water in the street pipe system. The lifting of this valve from the channel seat 10 opens connections with an alarm mechanism. The alarm is desired to operate only when a sprinkler or a leak has been the cause of the flowing of water into the system, and where the water movement may be caused 15 by one or more water hammers it has been customary to cause the water as it flows from the check valve to the alarm mechanism to pass through a receiving chamber 20 provided with a valve controlled waste port, the volume of the connecting piping and chamber being calculated to be large enough to hold as much water as will collect in it while the water hammer continues, taking 25 into account in the calculation the fact that water is differentially wasting through the waste port of the chamber at the same time that it is collecting there. One defect of such an arrangement has been that a false 30 alarm may be turned in by a close succession of water hammers owing to the fact that, as the waste port valve must be open when water first commences to flow so as to prevent too rapid an accumulation of water in 35 the chambers, a port large enough to rapidly empty it can not be used without preventing its filling at the desired rate when a sprinkler opens and an alarm is to be turned in.

50 The object of this invention is to provide means for emptying the receiving chamber of a channel check alarm valve at any rate necessary to enable the chamber to discharge

the accumulation of water resulting from each of a series of water hammers during 55 the time that that water hammer holds the channel check closed.

A further object of the invention is to reduce the water consumption of alarm valves consequent upon water hammers.

These two objects are accomplished by providing the receiving chamber with a waste port valve, which is closed during times of filling so that no change of its position takes place upon the opening of the 65 channel check valve and the entrance of water to the chamber and, subsequently, to the alarm mechanism, and which opens upon the reversal of the flow of water from passing into, to passing out of, the receiving 70 chamber. In this way no water is wasted by flow from this valve during the filling of the chamber and the effectiveness of the alarm does not depend in any degree upon the operation of any valve when the water 75 is admitted into the valve casing or into the receiving chamber nor does it depend upon the operation of any valve when the water in the receiving chamber or elsewhere 80 reaches some predetermined height so as to acquire a definite head; but is operated to discharge independently of the length of time during which the supply from the main 85 has been open. Moreover, the valve casing and receiving chamber are separate preferably so that the latter can be located at a 90 considerable elevation above the former. In this way a substantial head of water is secured for operating the waste port valve even when supplied only by the accumulation due to a water hammer.

The invention also involves other features as will appear hereinafter.

Reference is to be had to the accompanying drawings in which—

Figure 1 is a side elevation of sufficient parts of the entire system to show the relative arrangement thereof, parts being shown in central vertical section. Fig. 2 is a central vertical sectional view of the valve casing and inclosed parts on enlarged scale. Fig. 3 is a sectional view of a portion of the same on the line 3—3 of Fig. 2. Fig. 4 is a sectional view on the line 4—4 of Fig. 2, and Fig. 5 is a sectional view on the line 5—5 of Fig. 2.

The drawings show a usual construction of sprinkler system involving a pipe 10 fed from a main 11, the feed being controlled by a check valve 12 which operates in the usual way to allow water to flow into the sprinkler system from the main whenever the pressure in the former decreases materially, due to the opening of one or more of the sprinkler heads or a leak. As is usual also, a port or by-pass 13 is shown also covered by the valve 12 for the purpose of admitting water at the same time to the alarm device. This connected with a pipe 14. In the form shown in the drawings, this pipe 14 feeds into a valve casing 15 having a waste outlet 17 and a discharge pipe 18 which is connected with a vertical alarm pipe 19. This pipe 19 is connected with a receiving chamber 20 at the top which, when the water rises to the top thereof, causes the water to be discharged through a nozzle 21 against a wheel 22. In this case, this constitutes the alarm to be operated by the feeding of water out of the sprinkler system through the port 13. It will be understood, of course, that any other form of alarm, either electric or otherwise, can be substituted for the one shown, within the scope of this invention.

30 The casing 16 is divided by partitions into two chambers 23 and 24. The former communicates directly with the waste outlet 17, while the latter is separated from it.

Within the casing 15 is a filter 25 resting on a ring and below this in the casing 16 is a hollow valve 26 having two conical parts 27 and 28 fitting on seats 29 and 30, respectively, these seats being formed on the tops of two ports through horizontal partitions 40 in the casing 16. Extending down from the bottom of this valve 26 into the chamber 24 is a skeleton frame 31 which guides this valve in the port through the central partition of the casing 16. The bottom of the valve 26 carries a perforated plug 33 and below this the skeleton frame 31 supports an open bottomed sheet metal valve 34 adapted to close upwardly.

Under normal conditions, the valve 12 being closed, the valves 26 and 34 are kept in their lowermost positions by gravity and there is a free passage for the water from the upper casing 15 down into the chamber 24 and out through the pipe 18. It will also be observed that all the water which enters the casing 15 must pass out in this way and none of it, under these conditions, can be discharged directly through the outlet 17. It is clear, therefore, that if the valve 12 opens, either on account of the opening of a sprinkler head or on account of water hammer, the water will flow into the casing 15 down through the valve 26, bushing 33 and chamber 24 and will rise in the pipe 19. If

period, the water will rise into the chamber 20 until it operates the alarm and it will continue to operate the alarm until these conditions change.

It is to be noted that the water flows into the chamber 24 through the opening in the plug 33, which is small enough to keep the pressure in the chamber 15 higher during the flow of water therethrough than the pressure at the bottom of the pipe 19 due to the head above.

Whenever the channel seated check valve 12 closes, no matter to what this is due, the pressure of the water in the casing 15, due to the head in the main 11, is reduced because the valve seat 29 preferably is scored to permit leakage. If it is not desired to permit even this small waste of water the air entrapped in the top can be depended upon to insure the operation of the valve. If there is a material head of water in the pipe 19 this creates a back pressure in the reverse direction. This acts on the under side of the sheet metal cup-shaped auxiliary valve 34, raises the same against the seat in the bottom of the bushing 33, and thus fills this opening. The pressure on the bottom of the main valve 26 raises the valve and unseats it from the seats 29 and 30. This allows the water in the casing 15, as well as that from the receiving chamber 20, to rush into the chamber 23, out through the sides at 36, and down through the outlet 17, thus very rapidly emptying the whole device.

If the entrance of water into this device has been caused by water hammers, there will be a sufficient head of water in the pipe 19 to cause a rapid discharge within the interval between two successive hammers. Thus there is no danger of the alarm being operated, even by a numerous succession of water hammers. This result is due in part to the considerable elevation of the chamber 20 above the valve and its connection thereto by a long pipe of comparatively small capacity, and in part to the provision of a port area at valve 28 of sufficient size. It will be seen, therefore, that by this arrangement the operation of the valve is not dependent upon the flow of water from the main for a predetermined length of time, nor does the opening of the passage 13 in itself control the operation of the valve. In other words, even if something should happen to prevent the valve 26 from opening it would not prevent the alarm from being sounded the next time the valve 12 opened, nor would it waste much water. The only effect of any disarrangement of the valve 26 or the valve 34 would be to cause leakage and thus perhaps slightly delay the operation of the alarm or to hinder the final discharge of the water. Neither one of these actions would prevent the operation of the alarm whenever one of the sprin-

that the device consists of comparatively few parts and these parts of very simple character not requiring adjustment or manipulation except the automatic manipulation due to the system and they are of such a nature as to last indefinitely.

Although I have illustrated and described only one embodiment of the invention, I am aware of the fact that many modifications 10 can be made therein by any person skilled in the art without departing from the scope of the invention as expressed in the claims and I am also aware of the fact that the invention herein claimed can be carried out in 15 accordance with a companion application filed jointly by me and Hjalmar Carlson on even date herewith, for a valve for automatic sprinkler systems, etc., Serial No. 809,639. Therefore, I do not wish to be limited in 20 these respects, but

What I do claim is—

1. In a device of the character described, the combination with a receiving chamber arranged and adapted to pass water through 25 it to operate an alarm when water rises therein, of a valve casing for receiving water from a water supply system and supplying it to said receiving chamber, said valve casing having a waste outlet, and a valve in the 30 casing normally closing said waste outlet, said valve being located in position to be opened by the pressure of water from said chamber when the flow from the water supply system ceases, and arranged to close 35 when the chamber has emptied.

2. The combination with a receiving chamber having means for operating an alarm device when filled with water, and a check valve for admitting water to the chamber from a water supply system, of a valve 40 having a normally closed water outlet, said valve affording an unclosed passage for water from the check valve to said chamber and constituting means for opening a waste 45 passage for the water from the chamber upon the closing of said check valve, and for closing said waste passage when said chamber has emptied.

3. The combination with a receiving 50 chamber having means at its top for operating an alarm device, of a supply pipe from a water supply system having its inlet normally closed, a valve casing between said supply pipe and receiving chamber having a 55 waste outlet, and a valve in said casing normally closing said outlet, but normally permitting flow from the supply pipe to the chamber, and having means permitting the free discharge of the water from the receiving chamber and valve immediately upon the closing of said inlet.

4. The combination with a valve chamber 60 having a normally closed supply passage, a normally closed waste outlet, and an open 65 connection to a hydraulic alarm device, of a

valve in said casing for opening said waste outlet when said passage has been opened and then closed.

5. The combination with a valve casing having a normally closed supply pipe, a waste outlet and a connection normally connected with said casing for supplying a hydraulic alarm device, of means in said casing for simultaneously opening communication from the interior of said casing and 75 from said alarm connection to the waste outlet, said means being arranged to close normally by gravity.

6. In a device of the character described, the combination of a valve casing having an 80 inlet and provided with a port having a valve seat, a valve for closing said seat, said valve having a passage therethrough and extending beyond the seat, said casing having a chamber beyond said valve seat into which 85 said valve projects, said chamber having a second port, said valve having a portion fitting said second port and normally closing the same, a waste outlet connected with said chamber, and an open connection from said 90 second port for connection with an alarm device.

7. In a device of the character described, the combination of a casing having an outlet 95 and provided with a valve seat at the bottom, a valve for closing said seat, said valve being hollow and extending below the seat, said casing having a chamber below said valve seat into which said valve projects, the bottom of said chamber having a port, 100 said valve fitting said port and normally closing the same, a waste outlet connected with said chamber, an open connection from a point below said chamber for connection with an alarm device, said valve having a 105 port in the bottom thereof, and an upwardly operating valve below said port for closing the same when the pressure below it is greater than that above.

8. In a device of the character described, 110 the combination of a casing consisting of two parts, the upper part having an outlet and a port by which it communicates with the lower part, a screen in the upper part, the lower part of said casing having a chamber below said port, and a second chamber below that separated from it by a partition having a passage therethrough, means for normally closing said port and passage, and means whereby when the pressure in the 115 lower chamber exceeds that in the upper part of the casing both the port and passage will be opened.

9. The combination of a valve casing, a 120 normally closed supply pipe therefor, said casing having three chambers therein, one for receiving the water from said supply pipe, a waste outlet connected with the second chamber, and an open connection to a 125 alarm system connected with the third chamber.

ber, a valve in said casing, and means whereby when the water enters the first named chamber the valve will be held in position to allow the passage of water from the first chamber to the third chamber, and whereby when the pressure in the third chamber exceeds that in the first chamber said valve will be opened to allow the first and third chambers to discharge into the chamber which is connected to the waste pipe outlet.

10. In a device of the character described, the combination of a casing having three chambers therein, a valve normally closed but movable for disconnecting the second chamber from the other two, said valve having a passage for connecting the first and third chambers, an inlet connection into the first chamber, an open connection from the third chamber to an alarm system, said valve having an open end facing the open connection, and an auxiliary valve in position to close said open end when the pressure in the third chamber exceeds the pressure in the first chamber, whereby said auxiliary valve and main valve will be pushed back to permit the third chamber to discharge into the waste chamber, and the first chamber also to discharge into the waste chamber through said valve.

15. 11. In a device of the character described, the combination of a casing having three communicating chambers therein, the first chamber having an inlet connection, a valve movable for disconnecting the second chamber from the other two, said valve having a passage for connecting the first and third chambers, an open connection from the third chamber to an alarm system, and an auxiliary valve in position to close said passage in the valve when the pressure in the third chamber exceeds the pressure in

the first chamber, whereby said auxiliary valve and main valve will be pushed back to permit the third chamber to discharge into the second chamber.

45

12. The combination with a valve casing, of a normally closed pipe for supplying water to the casing, a normally closed valve in the casing arranged to be held in its normal closed position by the water when it enters the chamber on one side of said valve from the pipe, an elevated alarm device connected with the casing on the other side of the valve, means for allowing the water to flow freely from the casing to the alarm device when said valve is in said closed position, said valve having a surface on the side toward the alarm device for receiving the force of pressure from the alarm device, whereby when the pressure on said surface from the alarm device exceeds that on the first named side of the valve, said valve will be opened, said valve casing having a waste port connected with the alarm device and both sides of the valve when the valve is opened.

50

13. In a system of the class described, the combination of a chamber having an inlet, an inclosure, a stand pipe communicating with said inclosure, a waste space immediately between the chamber and inclosure and having ports leading to both, and a common valve for said ports having a restricted passage therethrough from the chamber to the inclosure.

60

In testimony whereof I have hereunto set my hand, in the presence of two subscribing witnesses.
